United States Patent Office

Des. 179,240
Patented Nov. 20, 1956

179,240

PAPER CLAMP OR THE LIKE

Samuel Boker, Brooklyn, N. Y., assignor to Novo-Plas
Manufacturing Co., Inc., Brooklyn, N. Y.

Application December 19, 1955, Serial No. 39,382

Term of patent 3½ years

(Cl. D74—2)

FIG. 1

FIG. 2

Fig. 1 is a top view of a paper clamp or the like showing my new design; and

Fig. 2 is a side elevation thereof.

I claim:

The ornamental design for a paper clamp or the like, substantially as shown.
